UNITED STATES PATENT OFFICE.

WILFRED I. OHMER AND JOSEPH LEITSCHUH, OF DAYTON, OHIO; SAID LEITSCHUH ASSIGNOR TO WILFRED I. OHMER, OF DAYTON, OHIO.

TICKET ISSUING, PRINTING, AND RECORDING MACHINE.

SPECIFICATION forming part of Letters Patent No. 695,116, dated March 11, 1902.

Application filed September 21, 1900. Serial No. 30,698. (No model.)

To all whom it may concern:

Be it known that we, WILFRED I. OHMER and JOSEPH LEITSCHUH, citizens of the United States, residing at Dayton, in the county of 5 Montgomery and State of Ohio, have invented certain new and useful Improvements in Ticket Issuing, Printing, and Recording Machines, of which the following is a specification, reference being had therein to the accompanying drawings.

This invention relates to certain new and useful improvements in ticket-machines.

The general object of this invention is to provide mechanism for issuing a ticket to a traveler for the distance he wishes to travel and also with the amount of fare stamped thereon, together with the time, &c., and at the same time store within the machine a duplicate ticket, whereby the exact number of 10 passengers buying tickets, as also the amount of fares received, may be quickly and accurately determined when the machines are returned to the proper authorities after a run has been made or after the close of a day's 15 business, and to this end duplicate banks, both of which are placed within a single shell or casing, are provided, one for issuing the ticket and the other for storing the ticket.

This invention further relates to an improved fare-indicator and mechanism for operating it, whereby the indicator must always be returned to zero before the conductor can operate the machine to issue another ticket, it being particularly understood that said machines are specially adapted for use by street-car conductors, &c.

Another object of this invention is to provide means for relieving the strain on the stored ticket-strip, due to the change in size 20 of the stored paper-roll and the consequent increase of winding speed of said roll over the speed of the feed-rolls through which said strip passes, thereby preventing the breakage of such stored strip.

45 This invention also relates to details of construction and organization hereinafter appearing, and particularly pointed out in the claims.

In the accompanying drawings, on which 50 like reference characters indicate corresponding parts, Figure 1 represents a perspective

view of our invention complete ready for use, with the supporting strap partly broken away; Fig. 1^a, a rear elevation; Fig. 2, a side elevation showing the outer casing in section, 55 the section being taken on the line *y*-*y* of Fig. 3 looking in the direction of the arrow, with parts broken away to facilitate illustration; Fig. 3, a rear elevation with the casing in section, the section being taken on the line *x*-*x* of Fig. 2; 60 Fig. 4, a side elevation of one of the banks of machines which is mounted within the casing; Fig. 4^a, a detail sectional view on the line *a*'-*a*' of Fig. 4; Fig. 5, a front or edge elevation of what is shown in Fig. 4; Fig. 6, a detail sectional view showing the ticket-printing mechanism, as also the fare-indicator, on an enlarged scale; Fig. 7, a plan view of what is shown in Fig. 6, with the fare-indicator removed; Fig. 8, an inverted plan view of what 70 is shown in Fig. 6; Fig. 9, a similar view to Fig. 4, but showing the opposite side of the machine; Fig. 10, a detail view of one form of track for guiding the inking and printing rolls into contact with the printing characters and also away from said characters, and Fig. 11 a longitudinal sectional view on the line *z*-*z* of Fig. 3 looking in the direction of the arrow.

The letter A represents a suitable casing 80 carrying a clock B. Within this casing are mounted two or more machines, one of which we will term an "issuing-bank," (indicated at C,) for the reason that tickets printed by its mechanism are issued through a slot or 85 opening D in the casing, while the machine indicated at E stores the ticket. This latter machine we will term a "storing-bank," inasmuch as the ticket printed by it is stored. Before entering upon a detail description of 90 these banks it will be observed that they are interconnected in such a manner that when one set of printing mechanism for printing a ticket is set the printing mechanism in the other bank will be likewise set, so that both banks are made to print duplicate tickets, one set issuing its tickets, while the other set stores its ticket, as above stated. Inasmuch 95 as the two banks are substantially alike, we will first describe the features common to both and will also use the same reference characters for such parts, after which we will de- 100

scribe parts which belong to one bank and not the other.

The letter F represents suitable side plates, held separated primarily by studs 6' or in any other suitable manner. Between these plates is carried the printing mechanism, hereinafter referred to. Upon the outside of each plate is mounted a pair of guides H, which support and hold in position sliding racks I and J, the rack I being a double rack and the rack J a single rack for the purpose hereinafter appearing. These racks are connected with each other by means of a swinging bracket K through rivets or studs L or in any other suitable manner, so that as one rack moves back and forth in its guides in a manner presently to appear the other one will likewise move. This swinging bracket carries an inking-roll frame M, which is hinged thereto, (see Fig. 11,) in which is mounted an inking-roll N. Such bracket also carries an impression-roll O. From each side of the inking-roll frame projects a stud or screw R, (see Figs. 2 and 3,) which is normally held in contact with the swinging bracket by means of a spring P, one end of which engages with the bracket, while the other end engages with such frame. As the swinging bracket M reciprocates back and forth between the plates 30 the impression-roll shaft 5, which projects into the tracks T, secured to the inner face of each side plate, acts to guide the inking and impression rolls into contact with printing characters which are formed on the face 35 of a printing-platen U, hereinafter described. As the swinging bracket advances the inking and impression rolls to the upper ends of the track T a latch V, one end of which is pivoted to each of said side plates, yields to permit 40 the shaft of the impression-roll to pass to the upper end of the track. As this takes place a spring X returns the latch across the track T, so that as the swinging bracket is reciprocated in the opposite direction the impression 45 and inking rolls will travel away from the printing-platen and to the lower end of the track T, in which latter position another trip V', pivotally carried by each track, will spring out of the way of the shaft to permit the impression-roll to pass. Immediately after this 50 takes place a spring X', acting on the trip V', will instantly swing across the track, so that when the swinging bracket is a second time operated it will be swung into contact 55 with the printing characters, as above stated.

In Fig. 10 we have provided a modified form of trip, as shown at V''. This latter form will never yield to permit the impression-roller to travel back in the portion of the track that 60 it has just passed, but acts as a positive stop to prevent it from doing so after the shaft S of the impression-roll has once passed the trip. From the above description it will be understood, of course, that on the inner face 65 of each of the side plates is mounted a track similar to the track T and that each track has a pair of trip devices either of the form as

represented at V and V' or of the form as indicated at V''.

Adjacent to the front portion of the track 70 T a printing-platen U is located, as heretofore stated. This printing-platen carries upon its face printing characters indicating the word "From," together with the number of the ticket, the word "Fare," the word 75 "Two," as also any printed matter, such as the name of the company, &c., desired. Immediately beneath the word "From" in the platen is formed a hole or opening 3, through which projects a station-printing roll 4, bearing the names of each of the stations along 80 the route to be traveled. Near the other end of the platen U is also formed another slot or opening 5, into which projects a station-printing roll 6, which also bears the names 85 of each of the stations along the route to be traveled. These station-printing rolls are adapted to be set so that any station from which the traveler is going may be turned into printing position in a manner herein- 90 after appearing in order that such station will be printed on a ticket to be issued to a traveler going from that station, while the station-printing roll 6 may also be turned so that the station to which such traveler is going may be 95 thrown into printing position, as also will hereinafter appear. Between each of the slots or openings 3 and 5 is formed another slot or opening 7, into which project dating-wheels 8, 9, and 10, respectively. The station-printing wheels are mounted upon shafts 11 and 12, respectively, which pass through the several banks and upon each of which are fixedly mounted the station-printing rolls, while the dating-wheels are mounted upon a shaft 13, 100 which also connects the several banks together. Between the slot 3 and the slot 7 is formed a smaller slot 14 in the platen U. In this slot projects a unit-fare-printing wheel 15, which prints the number of fare units upon 105 the ticket, such fare-printing wheel being turned so that the proper fare will be printed upon the ticket, as will hereinafter appear. Between the slots or openings 7 and 5 is mounted a clock-face 16, (see Fig. 8,) the 110 hands 17 and 18 of which are connected with time-operating mechanism, such as a clock, as will hereinafter appear. These time characters are also impressed upon the ticket as it 115 is being printed.

Referring to the ticket and the manner in which it is impressed upon the printing characters, it will be observed from Figs. 2, 5, and 11, particularly, that between each pair of side plates is pivotally mounted a spool 19, as shown 120 at 20. Upon this spool is wound a paper tape or strip 21, one end of which passes over the roller 22, mounted between the plates F, while its free end passes between the inking and impression rollers N and O and also between 130 a pair of issuing-rolls 23 and 24, respectively. The roller 23 is preferably formed of elastic material, such as hardened rubber, while the roller 24 is finely toothed. These rollers are

adapted to be rotated at the proper time to issue a paper strip through a slot or opening D, as will hereinafter appear. As the swinging bracket K carries the inking and impression rolls along the track T over the face of the printing characters such characters are inked by the inking-roll and the impression-roll acts to press the paper strip or tape up against the printing characters, whereby such paper strip or tape will receive the impressions from the printing characters. After this takes place the issuing-rolls 23 and 24 will issue the printed ticket from the machine in the manner presently to appear—that is, in one of the issuing-banks the ticket will pass from the machine, while in the storing-bank the paper strip will be stored, as will hereinafter appear.

Referring again to the printing mechanism, it will be observed that the station-printing-roll shafts are connected with each of the banks of machines within the casing, the station-printing-roll shafts 11 passing out through the casing at one side and carrying a knurled head 25, while the station-printing-roll shaft 12 also connects with each bank of machines and extends out through the casing at the opposite side and carries a knurled head 26 thereon. By taking hold of the knurled heads 25 and 26, one in one hand and one in the other, the station-printing rolls may be set so that any station may be rotated into printing position. The respective stations are indicated by pointers 27 and 28, the pointer 27 indicating the station from which a person is traveling, while the pointer 28 indicates the station to which the traveler is going. These pointers are mounted on their respective shafts 29 and 30. The shaft 29 carries a bevel-gear 31, meshing with the gear 32 on the station-roll shaft 11, while the shaft 30 carries a bevel-gear 33, meshing with the bevel-gear 34 on the station-printing-roll shaft 12. In order that the fare-wheel 15 in each bank may be set to indicate the amount of fare for any given distance, I provide a fare-wheel-setting shaft 35, (see Figs. 3 and 6,) which extends out through the casing and carries a knurled head 36 thereon. This shaft 50 also carries bevel-gears 37, one for each fare-printing wheel. These bevel-gears mesh with bevel-gears 38, carried by the fare-printing wheels 15. Thus when one fare-printing wheel is rotated so that the proper fare-printing character arranged around on the periphery of the fare-printing wheel comes into printing position on one wheel the same character will be in printing position on the fare-printing wheel of each bank.

From each fare-printing wheel extends a shaft 38', supported by bearings 39 and 40. (See Figs. 6 and 7.) On the outer end of the shaft 38' is mounted a bevel-gear 41, which meshes with the bevel gear-pinion 42, carried at one end of an indicator-operating shaft 43. The opposite end of said indicator-operating shaft also carries a bevel-gear 44, meshing

with a bevel-pinion 45, carried by an indicator 46, pivotally mounted on a stud 47. (See Figs. 4, 5, and 6 particularly.) This fare-indicator 70 46 carries a ratchet-wheel 48, with which engages a stop device 49. (See Figs. 4 and 5.) When the stop device is out of engagement with the ratchet-wheel, as will hereinafter appear, the fare-indicator may be quickly rotated to zero by means of a spring 50, one end of which engages with the fare-indicator, while the other end is connected with a stud 51, screwed into a cross-bar 51', carried by the side plates F. The stop device is pivoted upon 80 a bar 53, pivotally supported upon a stud 54, screwed into one of the guides H. With this bar engages one end of a push-rod 55, which projects through the casing and has mounted on its outer end a push-button 56. (See Figs. 85 1, 4, and 5.) As a conductor is about to take up a fare of a passenger he presses upon the push-button 56, thereby moving the bar 53, together with the stop device or detent 49, away from the ratchet-wheel 48. This permits the indicator to instantly rotate to such a position that zero appears through the sight-opening 57 in the casing A, it being understood that such indicator contains, in addition to the character zero, characters from 95 "1" to "9," or more, if desired, such characters indicating the number of fare units a passenger is required to pay, according to the distance to be traveled, such fare units being indicated at 58. (See Fig. 5.) At the same time the 100 push-button is operated to release the fare-indicator, so that it may return to zero, a wedge or cam 59, loosely mounted on the push-rod 55, is forced downward into contact with one arm 60 of a bell-crank lever by means of 105 a collar 61, secured to the push-rod 55 with a set-screw or in any other suitable manner. Consequently when the push-button is depressed the arm 60 of the bell-crank lever is thrown from its full-line position to its dotted-line position. (See Fig. 4.) This at once releases a detent 63, constituting the second arm of said bell-crank lever, from engagement with a spur-gear 64, meshing with the rack I. As the detent 63 of the bell-crank lever is thrown from engagement with the spur-gear 64 the rack I may travel in the guides H in a manner presently to appear. As the rack nears its upward stroke a stud or projection 67, carried by the rack, engages with 110 an extension 68 from the cam or wedge 59 and acts to elevate such wedge into contact with the collar 61. This movement of the cam permits the bell-crank lever to again assume its normal position, whereby the detent 63 again 115 engages the spur-wheel 64. As the rack, however, descends the spur-wheel 64 freely rotates by the detent 63, since such spur-gear travels in the opposite direction to that in which the detent holds it. As soon as the 120 press-button 56 is released a spring 65, pivoted upon the stud 66, acts to return the bar 53 to the position indicated in Fig. 4, thereby throwing the detent 49 into engagement with

the ratchet 58 on the indicator and also returning the push-button 56 to its normal up position, ready for the next operation.

Referring again to the connection between the fare-printing wheel and the fare-indicator, it will be understood that as the fare-printing wheel is set to print any particular fare in the manner above described that the fare-indicator will also be set at the same time, since the two are interconnected by means of shafts and gears, as above described. By properly arranging the numbers for representing the fares on the fare-indicator, they will correspond with like numbers on the fare-printing wheel, such numbers on such fare-printing wheel being indicated at 69. Consequently whenever a ticket is being printed with any particular fare such fare is also in indicating position through the sight-opening 57 in the casing A. The stop device 49 is pivoted, as shown at 49', and yields to permit the indicator to be set for any desired fare, yet at the same time prevents the indicator from turning after once being set back to zero without operating the arm 53, as also the stop device, away from the ratchet. A spring 49" acts to normally hold the stop in the path of the ratchet-wheel 58.

Referring now to the mechanism for operating the racks, it will be observed that to one side of the side plates F is pivoted a lever 70, which has a toothed segment 71, engaging with a spur-gear 72. This spur-gear is mounted on a shaft 73, which extends through the 35 side plate, forming a portion of one bank. Beside the gear-wheel 72, and also rigidly mounted upon the shaft 73, is mounted another gear-wheel 74, which is somewhat larger than the gear 72 and meshes with the rack J. 40 Consequently as the lever 70 is operated by taking hold of its upper end by hand the gear 74, as also the shaft 73, is made to rotate. On the opposite end of the shaft is mounted a gear 77, such gear being the same in size as the gear 74. This gear meshes with the rack I and acts to drive each rack back and forth in its guides. As heretofore stated, the rack I is a double rack and has the gear 64 connected therewith. This latter gear is loose upon the stud-shaft 73. Immediately in front of the gear 64 is mounted a similar gear 77', also loose upon said stud-shaft. These two gears are interconnected by a pawl 78 and a ratchet 79, one of which is carried by one 45 gear and the other of which is carried by the other gear. The gear 77' engages with a pinion 80, fixedly mounted upon a feed-roll shaft 81. This pinion also engages with a similar pinion 82, carried by a feed-roll shaft 50 83. These feed-roll shafts are mounted in the respective side plates and carry feed-rolls 23 and 24, respectively, the feed-roll 23 being preferably formed of rubber or other suitable yielding material, while the feed-roll 24 is formed of metal roughened to 55 constitute teeth or points, so that as the two roll together the metal teeth may somewhat press

into the elastic roll for the purpose herein-after appearing. As the paper roll or strip 21, above referred to, is drawn out of the machine by the rolls 23 and 24 after being printed upon, it is indented by the teeth on the roll 24. In actual practice this has been found to prevent the fresh ink on the ticket from being blurred and from running, and at the same time such feeding-rolls act to feed the paper in a regular and even manner. By connecting the pinion 80 with the gear 77' the feed-rolls are only operated as the racks descend on account of the ratchet connection 80 between the gears 64 and 77', the gear 77' remaining at rest when the racks are ascending. Thus with our organization the racks are by the detent 63 locked from movement until after the fare-indicator has been released, so that it turns to zero every time before another ticket can be issued. This prevents the possibility of the conductor issuing another ticket for the same fare for which the previous ticket was issued, as when the fare-indicator returns to zero at the same time the fare-printing wheel likewise returns to zero. Therefore in order that the proper fare may be indicated on the second ticket the conductor must operate the shaft 35 by means of the knurled head 36, which is mounted on the shaft outside of the casing A. This knurled head carries a pointer 85, which is adapted to indicate by a scale 86 the proper fare in printing position as also in indicating position, as heretofore mentioned.

We will now refer to the dating mechanism and the manner in which such mechanism is operated.

From Fig. 8 it will be seen, as above stated, that the shaft 13 has month and day-of-the-month printing wheels thereon—that is, it has one wheel with the names of the months and two wheels, one carrying the units of the months and the other carrying the tens of the months. Each of these wheels carries a ratchet 8', with which are adapted to engage pawls 9', normally held in engagement with said ratchets by means of springs 10'. The month-dating characters, as also the units and tens characters, are set by hand by taking hold of knurled heads, the head 102 being mounted upon a shaft 103, which extends through and into two banks within the casing. This knurled head carries numbers from "0" to "9," inclusive. For each bank a gear 104 is provided upon the shaft 103, such gear meshing with a gear 105, which is secured to or forms a part of the units-dating wheel 10. Thus by turning the knurled head 102 the units-dating wheel is also turned. The tens-dating wheel is also turned in like manner by means of a gear 106, which meshes with a gear 107, forming a part of the tens-dating wheel. The gear 106 for operating the tens-gear is mounted on a shaft 108, which also extends through the various banks and carries such a gear in each bank. On the outer end of this gear is also mounted a

knurled head 109, which may be turned the same as the knurled head 102, above described. Thus the units and tens dating wheels may be set without opening the machine. The 5 same is true of the month-dating wheel 8. This latter wheel is fixedly mounted upon the shaft 13, and the shaft extends through the several banks and also through the casing at one end and has mounted thereon a knurled 10 head 110. While this latter dating-wheel is being turned the units and tens dating wheels are held from rotating by means of the pawls 9'. Between the two banks is mounted a 15 clock, as shown at B, which carries a central stud or post 87, having a gear-wheel 88 mounted thereon, meshing with a gear-wheel 90, carried by a shaft 89, which extends into each bank, as indicated in Fig. 3. Should, however, more than two banks be employed, such 20 shaft may be extended into each of them. Within each bank and upon the shaft 89 is mounted a bevel-gear 91, such bevel-gear also meshing with bevel-gears 92, mounted on minute-shafts 93. Each of these minute-shafts 25 carries at its lower end a hand-printing character 17 and near its lower end a gear 94, (see Figs. 6 and 7,) which engages with a gear 95, supported by a bracket 96. Immediately beneath this gear 95 is also mounted a gear 30 97 of smaller diameter than the gear 95. This latter gear meshes with a gear 98, carried upon a hollow shaft 99, through which passes the minute-shaft 93. This hollow shaft we term an "hour-shaft," as it carries at its lower end 35 an hour-printing character or hand 18. If there are more than two banks, the time mechanism of each bank is connected with the shaft 89 in a similar manner.

From the above description it will be understood that in each bank is mounted a paper roll or strip which is adapted to receive impressions from printing characters, such printing characters indicating the stations from which a traveler is going and to which 40 he is going as also the date and the time when such ticket was issued, together with other suitable wording, and the amount or number of fares—as, for instance, "1 2 3 4 5" meaning five fare units, one fare unit being the 45 smallest amount charged for any distance, while those of higher denominations are simply multiples of such fare unit. Of course it 50 will be understood that any characters may be employed for indicating the amount of fare 55 and for printing such fare upon the tickets.

We will now refer to the storage-bank and will point out the peculiarities of such bank.

From Figs. 2 and 3 particularly it will be seen that within the storage-bank is mounted 60 a storage-roll 111, mounted on a shaft 112, carried by the side plates. This shaft projects at one side beyond the storage-bank and has mounted thereon a fixed clutch member 113, as also a pinion 114. The outer end 65 of the shaft is screw-threaded, as shown at 115, and carries a knurled nut 116, which may be screwed in or out on said shaft. Be-

tween the pinion and the knurled nut is mounted a spring 117. By screwing the knurled nut in more or less on the shaft the 70 spring 117 is compressed and acts to force the gear 114, as also the second member 118 of the clutch, in contact with the fixed member, it being understood that the member 118 is loose upon the shaft. Upon the shaft 73, 75 which extends through the storage-bank as well as the issuing-bank, we mount a gear 119, which meshes with an idler 120, supported on a stud 121, screwed into one of the side plates. The idler 120 meshes with the 80 pinion 111 and acts to drive said pinion, as also the loosely-mounted member 118 of the clutch, it being understood that the clutch and gear are connected with each other either integrally or otherwise. It has been found in 85 actual practice that as the storage paper-roll increases in size it will have a tendency to wind the paper on faster than it is fed from the carrying-roll by the feeding-rolls. This would soon cause the paper to break or tear 90 in two. It is to prevent this that we have devised our friction-clutch so that the tension may be adjusted by the knurled nut, so that when the pull upon the paper strip becomes excessive there will be more or less 95 slippage between the loose and fast members of the clutch.

We will now refer to the features embraced in the issuing-bank not embraced in the storage-bank.

Referring to Figs. 5 and 11, it will be observed that upon a bracket 122 is mounted a cyclometer 123 of the ordinary or any approved construction. This cyclometer carries a bifurcated crank-arm 124, between the 105 bifurcations of which a pin 125 is adapted to fit, such pin being carried by a crank-arm 126, mounted upon a shaft 127, to which the lever 70 is rigidly connected. This crank-arm is held in place by means of a set-screw or pin 110 128. Thus as the operating-lever 70 is moved back and forth the crank 126 is made to rock the cyclometer-crank, so that the cyclometer is operated once after every complete operation of the operating-lever. The numbers 115 are seen through a sight-opening 129 in the casing A. (See Fig. 1 particularly.) To the lower end of the issuing-bank is attached a bell 130. Adjacent to this is mounted a bell-clapper 131, pivoted to an arm 132, carried 120 by a shaft 133. This bell-clapper extends out to one side of its pivot, as shown at 134, and has one end of a spring 135 connected therewith, the other end of said spring being connected to the arm 132. This normally acts 125 to hold the clapper out of engagement with the bell when the arm 132 is in its normal position. At the opposite side of the storage-bank is mounted on the shaft 133 an arm 136, which carries a pivoted detent 137. A spring 138 130 normally holds said detent in engagement with a pin 139, extending from the arm 136. As the rack I is operated a pin 140 comes in contact with the detent 137. When the rack

moves from the position indicated in Fig. 4 to the upper end of the machine, the pin 140 acts upon the trip 137 to elevate the arm 136. This causes the arm 132 to swing and the bell-clapper to strike the bell. As the pin 140 moves past the trip in the opposite direction such trip yields to permit it to pass without acting upon the arm 136 and without sounding the bell. A spring 141, one end of which is secured to one of the side plates, while its other end is secured to the shaft, acts to partially rotate the shaft, so that the arm 136 contacts with a pin 142, projecting outward from one of the guide-bars II.

15 In describing the general features characteristic of both banks the fare-indicator is also described. It will be understood, however, that there is only one fare-indicator for as many banks as may be employed in a machine—that is, if there were a half dozen banks the shaft for setting the fare-printing wheel for each of said banks would at the same time set the single-fare indicator.

20 Having thus fully described our invention, 25 what we claim as new, and desire to secure by Letters Patent, is—

1. In a ticket-machine, the combination, with a casing, of a ticket-issuing bank and a ticket-storing bank mounted therein, printing 30 mechanism mounted in each bank, each printing mechanism comprising a fare-printing wheel and two independently-adjustable station-printing wheels, means for interconnecting said printing mechanisms, whereby when 35 one is operated the other is similarly operated, a paper-spool for each bank adapted to deliver a separate paper strip to its bank to be acted upon by said printing mechanism to form tickets, issuing-rolls for issuing the tickets from one of said banks from the casing, and a rotating spool for receiving and storing the pivoted ticket-strip from the other one of said banks, substantially as described.

2. In a ticket-machine, the combination, 45 with a casing, of a ticket-issuing bank and a ticket-storing bank mounted therein, printing mechanism mounted in each bank, each printing mechanism comprising a fare-printing wheel, two independently-adjustable station- 50 printing wheels and a time-printing wheel, means for simultaneously and similarly operating the corresponding printing-wheels of each bank, a paper-spool for each bank adapted to deliver a separate paper strip to its bank 55 to be acted upon by said printing mechanism to form tickets, issuing-rolls for issuing the tickets from one of said banks from the casing, and a rotating spool for receiving and storing the printed ticket-strip from the other 60 one of said banks, substantially as described.

3. In a ticket-machine, the combination, 65 with a casing, of a ticket-issuing bank and a ticket-storing bank mounted therein in fixed relation to each other, printing mechanism mounted in each bank, means for interconnecting said printing mechanisms, whereby

when one set of mechanism is operated the other is similarly operated, a paper-spool for each bank adapted to deliver a separate paper strip to its bank to be acted upon by said printing mechanism to form tickets, issuing-rolls for issuing the tickets from one of said banks from the casing, and a frictionally-driven storage-spool for receiving the printed ticket-strip from the other one of said banks, substantially as described. 75

4. In a ticket-machine, the combination, with a casing, of a ticket-issuing bank and a ticket-storing bank mounted therein in fixed relation to each other, printing mechanism 80 mounted in each bank, means for interconnecting said printing mechanisms, whereby when one is operated the other is similarly operated, a paper-spool for each bank adapted to deliver a separate paper strip to its bank to be acted upon by said printing mechanism to form tickets, issuing-rolls for issuing the tickets from one of said banks from the casing, feed-rolls for positively feeding forward the printed ticket-strip from the 85 other one of said banks, and a frictionally-driven storage-spool for receiving and storing said printed ticket-strip from the last-mentioned bank, substantially as described. 90

5. In a ticket-machine, the combination, 95 with a casing, of a ticket-issuing bank and a ticket-storing bank mounted therein, printing mechanism mounted in each bank, each printing mechanism comprising a pair of independently-adjustable station-printing wheels, date-printing wheels and time-printing 100 wheels, a clock mechanism for operating both of said time-printing wheels in unison, each of said banks being provided with a reciprocating bracket and each of said brackets being 105 provided with an inking-roll and an impression-roll, means for simultaneously operating the brackets of each bank, a paper-spool for each bank adapted to deliver a separate strip of paper between the printing mechanism and 110 impression-roll of said bank, issuing-rolls for each bank for engaging the paper strip thereof, and means for intermittently operating the issuing-rolls of each bank, said impression-rolls acting to press the paper strips into 115 engagement with the printing mechanisms after they are inked by said inking-rolls and when said issuing-rolls are at rest, substantially as described.

6. In a ticket-machine, the combination, 120 with a casing, of a ticket-issuing bank and a ticket-storing bank mounted therein, each of said banks comprising a printing mechanism, a reciprocating bracket having an impression-roll mounted therein, and an inking-roll yielding 125 connected with said bracket, and tracks for guiding said bracket, whereby its rolls operate in connection with the printing mechanism during the movement of the bracket in one direction only, a paper-spool adapted 130 to deliver a strip of paper between said printing mechanism and impression-roll, and feed-

ing-rolls for engaging and feeding said strip, means for simultaneously setting the printing mechanisms of each bank, means for simultaneously operating the reciprocating brackets of each bank, means for simultaneously and intermittently operating the feeding-rolls of each bank, and a storage-roll mounted in the storage-bank and having a frictional driving connection, whereby it is intermittently operated in unison with the feeding-rolls of said bank, substantially as described.

7. In a ticket-machine, the combination, with a casing, of a ticket-issuing bank and a ticket-storing bank mounted therein, printing mechanism mounted in each of said banks, each printing mechanism comprising a pair of independently-adjustable station-printing wheels, date-printing wheels, a fare-printing wheel, a time-printing wheel, and an apertured plate provided with printing characters, said printing-wheels extending through the apertures in said plate in printing position, a clock mechanism operatively connected with both of said time-printing wheels to operate them in unison, means for supplying a separate paper strip to the printing mechanism of each bank, means for inking said inking characters, means for inking the printing characters of each bank and for impressing the corresponding strip against said characters, means for operating the inking and impression devices of each bank in unison, means for delivering from the casing the printed ticket-strip of one bank, and means for storing the printed ticket-strip of the other bank, substantially as described.

8. In a ticket-machine, the combination, with a casing, of a ticket-issuing bank and a ticket-storing bank mounted therein, printing mechanism mounted in each bank and comprising a plate having slots or openings therein, a pair of station-printing wheels mounted in each bank and projecting through the slots or openings of the corresponding plate into printing position, a pair of shafts mounted in said banks extending through the corresponding station-printing wheels of each bank and projecting through the casing and provided with external operating means, whereby each set of station-printing wheels may be simultaneously and similarly adjusted in each bank, a paper-spool for each bank adapted to deliver a separate paper strip to its bank, means for inking each printing mechanism and for pressing the corresponding paper strip against said printing mechanism, whereby each strip receives a corresponding impression, feed-rolls for feeding said strips after printing, a frictionally-driven storage-roll in the ticket-storing bank, and means for simultaneously operating the several mechanisms of each bank, whereby the printed strip from one bank is issued from the casing to constitute a series of tickets, and the printed strip from the other bank is wound upon the storage-roll to constitute a record of

the series of tickets issued by the other bank, substantially as described.

9. In a ticket-machine, the combination, with a casing, of a ticket-issuing bank and a ticket-storing bank mounted therein, a shaft extending into each of said banks, a clock mechanism connected with said shaft, and time-printing characters in each bank connected with and operated in unison by said shaft, substantially as described.

10. In a ticket-machine, the combination, with a casing, of a ticket-issuing bank and a ticket-storing bank mounted therein, a clock mechanism and a shaft operated by said clock mechanism and extending into each of said banks, each bank being provided with an hour-shaft, a minute-shaft mounted in said hour-shaft and provided with a bevel-gear and a spur-gear, bevel-gears mounted on the shaft operated by the clock mechanism and engaging with the bevel-gears on the minute-shafts of the two banks, a spur-gear on the hour-shaft of each bank, intermediate gears between the spur-gear of said hour-shaft and of the corresponding minute-shaft, and printing characters mounted on the end of each shaft, substantially as described.

11. In a ticket-machine, the combination, with a casing having a plurality of banks mounted therein, of a fare-printing wheel mounted in each of said banks, means for interconnecting and setting said fare-printing wheels in the same printing position, an indicator, and means connecting said fare-printing wheels with said indicator, whereby when the fare-printing wheels are operated said indicator is set to agree with said fare-printing wheels, substantially as described.

12. In a ticket-machine, the combination, with a casing, of a plurality of banks mounted therein, a fare-indicator carried by one of said banks, a fare-printing wheel carried by each of said banks, means connecting said fare-indicator with the fare-printing wheel of its bank, a shaft connected with both of said fare-printing wheels for simultaneously setting said wheels and the fare-indicator, means for holding said indicator in indicating position, and means for releasing said indicator and returning the same to its initial position, substantially as described.

13. In a ticket-machine, the combination, with a casing, of a ticket-issuing bank mounted therein, a fare-printing wheel mounted in said bank, a fare-indicator carried by said bank, means for operatively connecting said fare-indicator with said fare-printing wheel, said indicator and wheel being each provided with a corresponding series of fare-indicating characters thereon, whereby when one of said characters is in printing position on the wheel a similar fare is in indicating position on the indicator, means for locking and releasing said indicator, and means for simultaneously returning said indicator and wheel to their initial position, substantially as described.

14. In a ticket-machine, the combination,

with a casing, of an issuing-bank mounted therein, a fare-printing wheel mounted in said bank, a fare-indicator pivotally mounted on said bank, means for interconnecting said fare-printing wheel and said fare-indicator, whereby when one is operated the other is similarly operated, means for operating said wheel and indicator, whereby the fare-printing wheel may be set to print any desired fare, and the fare-indicator to indicate the corresponding fare, a stop device for engaging with said indicator, a hand-operated device for disengaging said stop device from said indicator, and a spring for returning said indicator and fare-printing wheel to their initial position, substantially as described.

15. In a ticket-machine, the combination, with a casing, of an issuing-bank mounted therein and provided with a fare-printing wheel and a fare-indicator mounted to rotate therein and operatively connected for simultaneous movement, hand-operated means for simultaneously rotating said fare-printing wheel and indicator, whereby fares of any denomination may be printed and indicated, a push-rod, a stop device engaging with said indicator to hold the indicator and fare-printing wheel in indicating and printing positions respectively, means for connecting said push-rod with said stop device, whereby the stop device may be disengaged from said indicator, a spring to return said indicator and fare-printing wheel to their normal position upon the disengagement of the stop device, and a spring for returning said stop device into engaging position, substantially as described.

16. In a ticket-machine, the combination, with a casing, of an issuing-bank mounted therein, a fare-printing wheel and a fare-indicator rotatably supported on said bank, shafts and gearing connecting said wheel and indicator for simultaneous operation, and means for so operating said wheel and indicator, a ratchet secured to said indicator, a stop device comprising a pivoted pawl and a supporting-arm, said pawl being adapted to engage with said ratchet, a push-rod connected with said arm and adapted to disengage said pawl from said ratchet, a spring for returning said stop device to its normal position, and a spring for holding said pawl in position to engage said ratchet and prevent the same from being turned in one direction, while permitting it to turn in the opposite direction, substantially as described.

17. In a ticket-machine, the combination, with a casing, of an issuing-bank mounted therein, a fare-indicator, means for operating said indicator to indicate different fares, a stop device engaging with said indicator to hold it in such indicating position, a push-rod connected with said stop device, an operating-shaft carried by said bank and provided with a gear, a pawl engaging said gear, a cam device operated by said push-rod, means connected with said pawl and cam device to disengage said pawl from said gear,

whereby said gear may operate, and means to disengage said cam from said pawl to permit the pawl to engage the gear and lock the bank, substantially as described.

18. In a ticket-machine, the combination, with a bank mounted therein, of a bell-crank lever pivotally mounted in said bank, one arm of said lever constituting a pawl for engaging with an operating part of said bank, a push-rod, a cam or wedge, a collar mounted on said rod for engaging with said cam or wedge to move the same in one direction, said cam or wedge acting on the other arm of said bell-crank lever to disengage the pawl-arm thereof, means for operating said cam or wedge in the opposite direction, whereby its action upon said bell-crank lever ceases, and means for returning the pawl-arm of said bell-crank lever into engagement with said operating part, substantially as described.

19. In a ticket-machine, the combination, with a casing, of one or more banks mounted therein, each bank having side plates, each side plate provided with a track having a continuous track-groove therein, and stop devices pivotally mounted and extending across said track-groove, a reciprocating swinging bracket, a roller mounted in said bracket and having studs or projections fitting within said track-groove and adapted to throw said stop devices to one side when moving in one direction to permit the roller to pass, said stop devices acting to prevent the return of the roller along said portions of the track-grooves when moving in the opposite direction, substantially as described.

20. In a ticket-machine, the combination, with a track, of a yielding stop adapted to extend across said track, a reciprocating swinging bracket provided with a roller having a stud adapted to travel in said track and engage said stop to throw the same from across the track when said roller is traveling in one direction, to permit the roller to pass, and a spring for returning said stop across the track to prevent the passage of the roller in the opposite direction, substantially as described.

21. In a ticket-machine, the combination, with a casing having one or more ticket-banks mounted therein, each bank having a pair of side plates provided with track-grooves in their opposite inner faces, each groove being continuous and composed of parallel portions connected at their ends, of a pair of yielding stop devices at the opposite ends of said parallel portions, said stop devices being adapted to yield in one direction only, and a reciprocating swinging bracket provided with an impression-roller having studs projecting into said tracks, whereby said roller is permitted to travel along each of said parallel portions in one direction only, substantially as described.

22. In a ticket-machine, the combination, with a casing, of a ticket-issuing bank and a ticket-storing bank mounted therein, operating means connected with both of said banks,

whereby when one bank is operated the other bank will be similarly operated, means for automatically locking both banks after each operation, and hand-operated means for un-locking said banks to permit a successive operation thereof by said operating means, substantially as described.

In testimony whereof we affix our signatures in presence of two witnesses.
